CLAIM

The ornamental design for a transdermal foot patch, as shown and described.

DESCRIPTION

FIG. 1 is a top perspective view of a transdermal foot patch. FIG. 2 is a top plan view of the transdermal foot patch depicted in FIG. 1.

FIG. 3 is a bottom plan view of the transdermal foot patch depicted in FIG. 1.

FIG. 4 is a right side view of the transdermal foot patch depicted in FIG. 1.

FIG. 5 is a left side view of the transdermal foot patch depicted in FIG. 1.

FIG. 6 is a front side view of the transdermal foot patch depicted in FIG. 1.

FIG. 7 is a back side view of the transdermal foot patch depicted in FIG. 1; and,

FIG. 8 is another perspective view of the transdermal foot patch depicted in FIG. 1 in a state of use positioned on a user's foot.

The broken lines in FIGS. 1–7 show portions of the transdermal foot patch that form no part of the claimed design. The broken lines in FIG. 8 showing a human foot are directed to environment and form no part of the claimed design. As shown, the transdermal foot patch may be used by being positioned on a user's foot.

1 Claim, 4 Drawing Sheets
